UNITED STATES PATENT OFFICE.

ARTHUR B. GOODSPEED, OF HADLYME, CONNECTICUT, ASSIGNOR TO INDUSTRIAL DEVELOPMENT COMPANY, OF NEW YORK, N. Y., A CORPORATION OF NEW YORK.

INTERNAL-COMBUSTION ENGINE.

1,302,653.

Specification of Letters Patent.

Patented May 6, 1919.

Application filed February 9, 1918. Serial No. 216,326.

To all whom it may concern:

Be it known that I, ARTHUR B. GOODSPEED, a citizen of the United States, residing at Hadlyme, in the State of Connecticut, have 5 invented certain new and useful Improvements in Internal-Combustion Engines, of which the following is a specification, reference being had to the accompanying drawing, forming a part hereof.

10 This invention relates to internal combustion engines of the general type of that shown in Letters Patent of the United States No. 857,730, dated June 25, 1907, and has for its object to improve the ignition in engines of this type. In accordance with the invention a volume of gas or of gaseous mixture, supplied from a source external to the main fuel supply, that is, to the combustion chamber of the engine, is at the proper time 15 ignited and discharged directly into the fuel mixture to ignite the same. By supplying the igniting charge from a source external to the combustion chamber of the engine and so constructing the engine as to permit the igniting charge to be discharged directly into the combustion chamber, all difficulties incident to the presence of exhaust gases in the combustion chamber are eliminated and it becomes unnecessary to provide a garret or 20 space into which such exhaust gases may be driven ahead of the fresh charge. Ignition also is thereby made more certain and more exactly controllable in relation to the movement of the main piston. The invention will 25 be more fully explained hereinafter with reference to the accompanying drawing in which it is illustrated and in which the single figure shows, in vertical section, so much of an internal combustion engine of the type 30 referred to as is necessary to enable the invention to be understood.

The engine in which the invention is embodied may be of any suitable construction. In the engine shown in the drawing the 45 water-jacketed main or working cylinder *a* receives the usual trunk piston *b* which is connected by a pitman *c* to a crank-shaft *d*. The cylinder may be provided, substantially as in the engine shown in said Letters Patent 50 No. 857,730, with an exhaust port and valve, as at *e*, and with an inlet and valve for the admission of auxiliary air. The main charge is received through the head of the engine 55 through the valve shown at *g*, a connection to an oil supply being indicated at *g'* and a

connection to an air supply being indicated at *g''*. The charge is delivered under pressure into a combustion chamber *a'* which communicates through a narrower passage *a''* with the compression space at the head of 60 the cylinder.

At a convenient point in the wall of the combustion chamber, preferably in the somewhat narrow throat *a''*, is formed a port *h* which communicates with a cylinder *h'*, a 65 plunger *k* being located in the cylinder *h'*. Located in the wall of the cylinder *h'*, at such a point that it will be uncovered by the plunger *k* in its rearward stroke, is an inlet port *h''* through which the igniting charge 70 may be admitted. As shown in the drawing, the admission of the igniting charge may be controlled by a needle-valve *h'''* which has a connection, as at *h''*, to an oil supply and a connection, as at *h'''*, to an air supply, preferably under pressure. The plunger *k* may be reciprocated in proper timing relation to the movements of the piston *b*, by any suitable means. As shown, the outer end of the plunger is connected by a link *k'* to a bell- 80 crank lever *k''*, the short arm of which is connected by a link or pitman *k'''* to a plunger *k''''*, the latter being reciprocated by a steep cam *k''''* on an auxiliary cam-shaft *k'''''* which is driven by any suitable means from the 85 crank-shaft *d* and in proper synchronism therewith. The spring *k''''''* acts upon the bell-crank *k''* in opposition to the cam *k''''* and the construction is such that the rearward movement of the plunger *k* is relatively slow while 90 the forward movement is very quick.

In order to prevent the passage into the cylinder *h'* of any exhaust gases from the combustion chamber of the engine and to insure the formation within the cylinder *h'*, 95 during the rearward movement of the plunger *k*, of a vacuum of proper degree, a spring-pressed valve *m* is located in the engine head, in alignment with the port *h* so that, during the rearward movement of the plunger *k*, the port *h* is kept closed, while during the forward movement of the plunger the igniting charge in the cylinder *h'* is delivered into the combustion chamber 100 of the engine, being spread fanwise with the tapered head of the valve *m*, so as to insure ignition of the main charge throughout its volume.

The cam *k''''* being properly timed with respect to the movement of the piston *b* it 110

- will be evident that during the rearward movement of the piston b the plunger k is withdrawn somewhat slowly so that a partial vacuum is formed within the cylinder h' .
- 5 As soon as the port h^2 is cleared by the plunger the igniting charge is discharged into the cylinder h' and thereupon the plunger is kicked forward by the cam k^5 with such rapid movement as to effect compression of the igniting charge within the cylinder h' to such a degree as to bring about ignition thereof, the igniting charge in a state of combustion being forced out from the cylinder h' , as the plunger k approaches the limit of its forward stroke, into the combustion chamber a', a^2 , whereby ignition of the main charge is accomplished, as already set forth.
- 10 It will be obvious that various changes in details of construction and arrangement may be made to suit different conditions of use and that the invention, except as pointed out in the accompanying claims, is not limited to the precise details of construction and arrangement shown and described herein.

I claim as my invention:

1. In an internal combustion engine, the combination of a working cylinder, means to introduce the main charge at the head end of the cylinder, an igniting cylinder in communication with the combustion chamber of the working cylinder, means to admit an igniting charge to the igniting cylinder from a source external to the combustion chamber of the engine, and means to compress and ignite the igniting charge within the igniting cylinder and to discharge it in a state of combustion into the combustion chamber of the working cylinder.
2. In an internal combustion engine, the combination of a working cylinder, means to introduce the main charge at the head end of the cylinder, an igniting cylinder in communication with the combustion chamber of

the working cylinder, a valve normally closing communication between the igniting cylinder and the combustion chamber and opening toward the combustion chamber, means to admit the igniting charge to the igniting cylinder from a source external to the combustion chamber of the engine, and means to compress and ignite the igniting charge within the igniting cylinder and to discharge it in a state of combustion into the combustion chamber of the working cylinder.

3. In an internal combustion engine, the combination of a working cylinder, means to introduce the main charge at the head end of the cylinder, an igniting cylinder in communication with the combustion chamber of the working cylinder, a plunger in said igniting cylinder, said igniting cylinder having a port uncovered by the plunger in its rearward movement, and means to admit an igniting charge to the igniting cylinder through said port from a source external to the combustion chamber of the engine.

4. In an internal combustion engine, the combination of a working cylinder, means to introduce the main charge at the head end of the cylinder, an igniting cylinder in communication with the combustion chamber of the working cylinder, a plunger in said igniting cylinder, said igniting cylinder having a port uncovered by the plunger in its rearward movement, means to admit an igniting charge to the igniting cylinder through said port from a source external to the combustion chamber of the engine, and a valve normally closing communication between the combustion chamber of the working cylinder and the igniting cylinder and opening toward the combustion chamber of the working cylinder.

This specification signed this 1st day of February 1918.

ARTHUR B. GOODSPED.
